UNITED STATES PATENT OFFICE.

JAMES H. EGAN, OF VENTNOR CITY, NEW JERSEY.

SLOT MACHINE.

Application filed January 5, 1924, Serial No. 684,566.

To all whom it may concern:

Be it known that I, JAMES H. EGAN, a citizen of the United States, residing at Ventnor City, in the county of Atlantic and 5 State of New Jersey, have invented certain new and useful Improvements in Slot Machines, of which the following is a specification.

This invention relates to coin controlled 10 machines of the type particularly adapted and intended for vending what are known as "checks", in exchange for cash, and used for example at soda fountains, where the purchaser may deposit a coin of a certain 15 value in the machine and receive in return a check which can be delivered to the soda clerk in exchange for the goods.

The present machine is in some respects 20 an improvement on the machine shown in my U. S. Patent No. 1,365,469, dated January 11th, 1921.

The present improvements relate especially to a means for closing the coin chute when the supply of checks is exhausted and 25 also for closing said chute when the pile of coins in the machine reaches such a point that the operation of the machine might be interfered with should additional coins be deposited. That is to say, when the machine becomes, as it might be termed, full of 30 coins, further deposits will be prevented. The word full does not mean that the whole casing must become full but only that the pile of coins reach such a point, as above 35 stated, that it might interfere with the escapement devices.

A further object of the invention is to improve the casing of such slot machines and the means for mounting the same upon a 40 base, and for connecting the various parts so that the casing cannot be removed or opened by unauthorized persons. This feature includes a rotatable mounting for the machine so that it can be presented at any 45 angle desired.

Various other objects will appear from the following description and the accompanying drawings.

In the drawings, Fig. 1 is a front elevation of the machine. Fig. 2 is a section partly broken away. Fig. 3 is a sectional plan view of the bottom plate of the machine, the parts above the same being removed. Fig. 4 is a detail in section of the 50 upper part of the casing on the line 4-4 of Fig. 6, illustrating the means for locking

the casing to the machine proper enclosed within the same. Fig. 5 is a side elevation, the casing being in section, illustrating the device for closing the coin chute. Fig. 6 is 60 a side elevation of the machine with the casing in section as viewed from the front. Fig. 7 is a partial side elevation of the same as viewed from the rear with the casing in 65 section. Fig. 8 is a detail in section on the line 8-8 of Fig. 5. Fig. 9 is a detail in top view of the slot mechanism with a part of the casing in section.

The casing of the machine includes a top 70 6 and side walls 7 fitting upon a metal base 70 plate 8 which latter supports the operative parts of the machine to be hereinafter described. The base plate 8 is mounted on a pivot 9 projecting from a plate 10 which may be fastened to a counter 11 by screws 75 12 or the like, whereby the casing or the machine as a whole can be rotated on the post 9 and thereby turned to any desired 80 position. The machine is retained on the pivot against unauthorized removal therefrom by means of a sliding latch 13 consisting of a plate with a notch in the end adapted to engage a neck 14 under a head 15 on the pin 9. The latch is slidable in a 85 guide 16, and when a door 17 in the rear wall of the casing is opened this latch can be slid in or out to engage or disengage the pin. The door 17 is provided with an ordinary lock. When the latch is released, the whole 90 machine can be lifted off the pin 9.

To lock the casing to the interior structure of the machine, I provide a sliding latch bolt 18, mounted in guides 19 and 20 fastened between plates 21, which are attached to the base plate 8 by means of legs 22 and feet 23. This latch 18 is also accessible when the door 17 is opened and may be pushed in to engage in a hole in a bracket 24 fastened to the under side of the top 6 of the casing. By these means the whole 100 outer casing is normally locked to the inner parts of the machine, but the casing can be unlocked and lifted off by opening the door 17 and pulling the bolt 18 outwardly to disengage it from the depending bracket 24. 105 When so removed, the interior mechanism is exposed. It will be noted that the devices for locking the machine on the support 9, and for locking the casing upon the machine, are only accessible thru the door 17 at the 110 back, and that no screws or other devices have to be removed to separate the parts,

The machine as disclosed includes three units for delivering checks or tokens of different values, say one a 5¢ check, another a 10¢ check, and another a 25¢ check, appropriate slots being made in the front of the casing, as indicated at 25, to receive corresponding coins, the checks however being delivered onto a tray 26 thru holes 27 in the front wall of the casing.

10 Except with respect to the value and size of the checks and coins, the units are all alike, and a description of one will answer for all.

15 The checks will consist of round pieces of metal, and they are fitted into the machine according to their respective denominations thru a slot at 30 at the under side of the upper end of a chute 31, the slot 30 being located at the rear of the machine under an extension 32 on the back of the casing, which extension is open on the under side so that the checks can be pressed up until they slip past a spring 33 in the chute, and above the slot, and will thence roll down the chute 20 into the recesses in a star wheel 34 from which they are delivered one by one thru the opening 27 to the delivery tray 26. The escapement for the star wheel comprises a lever 35 pivoted at 36 and having an offset finger 37 which projects thru an opening 38 in the side plate 39 of the mechanism, the lever 35 having an offset finger upon which a coin will drop to trip the lever when the coin falls from the coin chute 41, the 25 lever being weighted as indicated at 42 to restore the same after each tripping operation. The upper end of the coin chute 41 registers with a slot 44 in the front of the casing, and when a coin is inserted it will 30 roll down the chute and drop from the lower end 45 of the chute onto the finger 40 of the escapement lever 35 as above described.

45 The device for closing the mouth of the coin chute will now be described: A sheet metal member is pivotally mounted on a bracket 50 fastened to the side of the chute 31, one of the pivots being indicated at 51 and the other at 52. This sheet metal member includes an arm 53 which projects forwardly and upwardly, and has at its end an offset finger 54 which may swing inwardly or laterally across the mouth of the chute 41. The member also has a depending arm 55 with a paddle-shaped enlargement 56 at its lower end which forms a weight tending to hold the member in vertical position, in which position the finger 54 is located out of alignment or withdrawn 50 from in front of the mouth of the chute 41. But this action may be prevented by a bent lever 60 which is fulcrumed at 61 and which presses sidewise or outwardly against a finger 63 projecting from the arm 55 of the 65 sheet metal member referred to. This lever

60 projects into a cut out portion 64 of the chute 31, directly above the star wheel 34, in such position that the lever 60 rests or rides upon one of the checks C at that time resting in the chute above the star wheel, 70 and under such conditions the lever 60 is lifted to such an extent that its finger 62 is retracted from the finger 63 and the sheet metal member then hangs in such position that the finger 54 is out of line with the 75 entrance to the chute 41, and accordingly coins can be deposited and the escapement operated. But if the supply of checks rolling down the chute 31 becomes exhausted, the lever 60 will drop and its weight is 80 sufficient to swing its arm 62 against the arm 63 and swing the arm 55 and weight 56 laterally and outwardly, swinging the sheet metal member on its pivots 51 and 52 and thereby causing the finger 54 to swing across the coin chute and prevent the deposit of any coin therein. And this condition continues until by depositing additional checks the lever 60 is swung up, permitting the sheet metal member to swing to vertical 85 position and thereby opening the entrance to the coin chute, as above described, the tendency of the sheet metal member being to swing to position to open the coin chute except when prevented by the action and 90 greater weight of the lever 60.

95 Furthermore, as the coins drop from the chute 41, to operate the escapement as above described, they collect in a pile on the base plate 8. As this pile rises it will 100 in time reach the elevation of the paddle-shaped member 56 and finally the coins will press against the inner side of said paddle, referring to Fig. 5, and as the pile accumulates the coins lodging against this paddle will then swing the same outwardly or toward the observer in Fig. 5, thereby swinging the sheet metal member on its pivots 51 and 52 across the mouth of the coin chute. This, therefore, stops the further 105 deposit of coins in the chute, and the pile of coins must be removed from the lower part of the machine, permitting the sheet metal member to resume its vertical position with an unobstructed coin chute. 110

115 It will therefore be seen that a device is provided which may be operated either when the supply of checks becomes exhausted, or when the deposit of coins becomes excessive, to close the coin chute and prevent further operation until either condition is remedied.

120 A register operating mechanism may be associated with the mechanism illustrated, such for example, as that shown in my U. S. Patent No. 1,459,879, dated June 26th, 1923, but as this is not essential to the present invention a description and illustration thereof have been omitted.

125 It will be understood that the sheet metal

member for closing the coin chute, as above referred to, is very delicately balanced, so that it will operate under slight pressure to close the chute, but when the pressure is released it will swing easily to vertical position with the coin chute unobstructed.

The invention is not limited to the particular construction shown, but is capable of various modifications within the scope 10 of the following claims.

As stated, several units may be assembled in the same machine, according to different denominations, and in this case mechanisms may be arranged rights and lefts, to 15 stand beside each other, but this involves merely the reversal of the structures of the different parts.

I claim:

1. The combination with a coin chute, a 20 chamber into which it delivers, and an article delivery mechanism controlled by coins deposited in the chute, of a device to prevent the deposit of coins in the chute,

and separate means actuated one by the exhaustion of the articles to be delivered and 25 the other by an excessive accumulation of coins in said chamber to operate said device.

2. The combination stated in claim 1, said means including a paddle shaped lever the lower end of which hangs into said chamber and the upper end of which has a projection adapted to be swung across the coin chute, and another lever bearing against 30 said paddle shaped lever and having a portion located in the path of articles in the 35 article delivery mechanism and adapted to be moved to inoperative position by said articles and to move to operative position and swing the paddle shaped lever in the absence of such articles. 40

In testimony whereof, I affix my signature in presence of two witnesses.

JAMES H. EGAN.
